DRAPERY PLEATER HOOK

Philip Rosenzweig, Detroit, Mich.

Application November 13, 1957, Serial No. 48,470

Term of patent 7 years

(Cl. D21—1)

Fig. 1 is a front elevational view of a drapery pleater hook embodying my new design.

Fig. 2 is a side elevational view thereof.

Fig. 3 is a top plan view thereof.

I claim:

The ornamental design for a drapery pleater hook, substantially as shown.
